A. B. REAVIS
ATTORNEY

UNITED STATES PATENT OFFICE.

LOUIS G. MILLER, OF BETHLEHEM, PENNSYLVANIA, ASSIGNOR TO BETHLEHEM STEEL COMPANY, OF BETHLEHEM, PENNSYLVANIA.

CLOSURE FOR RECEPTACLES.

Application filed May 20, 1924. Serial No. 714,538.

My invention relates to covers or closures for receptacles or storage tanks, such, for example, as tank cars, and it has for an object to provide apparatus of this character which shall be safe to manipulate.

A further object of my invention is to provide a cover having a bayonet-like type of connection with respect to a tank or receptacle.

19 A further object of my invention is to provide a cover requiring loosening in an outward direction before the cover may be disengaged from a receptacle by turning movement, thereby permitting the gradual escape 15 of gas from the receptacle incident to the removal of the cover.

Apparatus made in accordance with my invention is illustrated in the accompanying drawings, forming a part of this application, 20 in which:

Fig. 1 is a plan view of a dome lid in its closed position on the receptacle;

Fig. 2 is a part sectional view, across line II—II in Fig. 1, of the dome ring, dome 25 lid, receptacle, and the means adapted for securing the dome lid in its closed position;

Fig. 3 is a sectional view of a ring showing the safety stop in elevation;

Fig. 4 is a part plan view of the dome lid, 30 dome ring and receptacle with a section of the bracket projection corresponding to line IV—IV in Fig. 5; and,

Fig. 5 is a detail sectional view across line V—V of Fig. 2, showing bracket projection, 35 dome lid lug and safety stop.

In Figs. 1, 2 and 5, I show the interior shell A of the receptacle, having the usual opening B provided therein. A circular dome ring consisting of a main body portion C, a 40 depending annular flange D to correspond with the opening B, a suitable number of vertically upstanding projections E, equally interspaced around the periphery of the body C, and a suitable number of stops F projecting at points intermediate between the projections E. The projections E are of right angled section (as shown in Fig. 4) and have their members joined by two parallel flange portions or webs G and G₁ (Figs. 2 and 5). 45 These webs are drilled to freely accommodate tap bolts H, sufficient clearance being left between the parallel webs to permit the interposition of nuts I.

The dome ring is riveted to the inner shell 50 A of the receptacle near the edges of the

opening B. The edge of the outer jacket J is preferably welded to the dome ring, slightly overlapping the rim thereof at every point on its periphery. The dome lid or closure consists of a body portion K, a depending annular flange L adapted to fit within the dome ring flange D, a peripheral flange M with lugs N extending therefrom, equally spaced, and in number to correspond with the projections E of the dome ring, and two upstanding pins O adapted for a suitable key bar to facilitate 60 rotary movement of the dome lid.

The lower face of the peripheral flange is grooved for insertion of a suitable gasket P, so as to effect a close joint between dome 70 ring and lid when the lid is in its closed position. The body of the dome lid is dished outwards in the usual manner, the reinforcement of the lugs N being effected by the radial ribs Q.

An important feature of my invention resides in the position of the safety stops F on the dome ring. These stops are of the shape shown in Fig. 3 and occupy a position intermediate between the projections as shown in 80 Fig. 1. The distance between the right angle faces of the stops F and the edges of the webs G₁ is appreciably less than the width of the lugs N. Owing to this, it is impossible to turn the dome lid about its axis when in 85 its closed position far enough to disengage the lugs N from the webs G₁. If, however, the dome lid be raised, by the partial withdrawal of tap bolts H, so that the lugs N may clear the top of the safety stops F, a sufficient turning movement can be given to the dome lid to effect the complete disengagement 90 of the lugs N from the said webs of the projections E. Therefore, in the event of an accumulation of gas under pressure in the receptacle, gradual withdrawal upwards of the tap bolts H by the slackening back of the nuts I, permits of the gradual raising of the dome lid and consequent release of the gas pressure around the joint P. The release of this 95 pressure is thereby insured before the complete disengagement of the lugs can be effected.

When securing the dome lid in its closed position, the tap bolts are lowered so as to 105 bear on the lugs of the dome lid. The necessary compression at the gasket joint P is obtained by the thrust of the nuts I against the under faces of the upper webs G.

Having thus described my invention what I 110

claim as new and desire to secure by Letters Patent is:

1. In a closure construction, the combination of a seat member, a closure member, radial tongues carried by the closure member, members carried by and extending outwardly from the seat member and provided with transverse slots adapted to receive said tongues, means carried by said members for exerting pressure on the tongues to urge the closure member into seating relation with respect to the seat member, said means being operable independently of the movements of the closure member and means for preventing disengagement of the tongues from the slots by angular movement of the closure member until the pressure-exerting means have been relieved to a predetermined extent.
2. In a closure construction, the combination of a seat member, a closure member, a plurality of radial tongues carried by the closure member, a plurality of outwardly extending members connected to the seat member and having transverse slots adapted to receive said tongues, the tongues being engaged in and disengaged from the slots by angular movement of the closure member, means carried by the outwardly extending members for exerting pressure on the tongues to firmly engage the closure and seat members, and lugs carried by the seat member and spaced from the entrance sides of the slots distances less than the widths of the tongues and having their top surfaces disposed outwardly of the bottom surfaces of the tongues when the closure member is seated.
3. In a closure construction, the combination of a seat member, a closure member, a plurality of outwardly-extending and spaced-apart tongues carried by the closure member, a plurality of upstanding members connected with the seat member, spaced similarly to the tongues, and defining tongue-receiving slots, means carried by the upstanding members for exerting pressure on the tongues to firmly engage the closure and seat members, and lugs carried by the seat member and disposed to one side respectively of each slot a distance less than the width of the corresponding tongue, and having their respective top surfaces disposed outwardly of the inner surfaces of the tongues when the closure member is seated with respect to the seat member.
4. In a closure construction, the combination of seat and closure members having telescopic flanges, a circumferential series of spaced-apart tongue members carried by the closure member, a plurality of upstanding members having lateral flanges which define tongue-receiving spaces, screws extending through the flanges for firmly engaging the seat and closure members, and lugs connected with the seat member and spaced from the entrance sides of the spaces distances less than the widths of the respective tongues for the corresponding spaces, and having their tops spaced outwardly of the inner surfaces of the tongues when the closure member is seated with respect to the seat member.

In testimony whereof I hereunto affix my signature this 15 day of May, 1924.

LOUIS G. MILLER.
